UNITED STATES PATENT OFFICE.

PETER L. MARKEY, OF CHICAGO, ILLINOIS.

CUFF FASTENER.

Application filed November 12, 1927. Serial No. 232,754.

This invention relates to improvements in cuff fasteners and it consists of the matters hereinafter described and more particularly pointed out in the appended claims.

5 The primary object of the invention is to provide a small, neat compact fastener to properly secure the lateral margins of a cuff together without the aid of the usual button holes and in a manner permitting the 10 ready change of the fold line of the cuff so that the adjacent soiled and worn portions thereof may be concealed from view and also whereby the shirt sleeve may be adjusted within certain limits as to its effective length.

A further object of the invention is to provide a device of this kind which may be readily produced from wire and may be readily applied to a cuff and which, while it is easily removable when desired, cannot easily become lost when applied to a cuff.

These objects of the invention, as well as others, together with the many advantages thereof will more fully appear as I proceed 25 with my specification.

In the drawings:

Fig. 1 is a perspective view on an enlarged scale of the improved fastener as when in operative position upon the cuff of a shirt.

30 Fig. 2 is a view in side elevation of the two units of the fastener in the position they occupy when operatively engaged upon a cuff.

35 Figs. 3, 4 and 5^a are detail perspective views of the various parts embodied in a fastener unit and each of which will be more fully referred to later.

Fig. 5 is a top plan view of one of the units.

40 Fig. 6 is a longitudinal vertical section through the same on the line 6—6 of Fig. 5.

Fig. 7 is a view in side elevation of one of the units with the parts in the relations they bear in Fig. 6.

45 Fig. 8 is a view similar to that shown in Fig. 7 with the parts in the relation they occupy in Fig. 5.

My improved fastener consists of two separate units each adapted to be removably but securely attached to the lateral margins of the well known soft or turned over cuff of a shirt and when so attached to be detachably connected together to hold said margins of the cuff together. Both units are substantially alike and each embodies an open wire frame to embrace opposite sides of

a cuff margin and on that end of each frame on the outer side of said cuff margin is a lever actuated means including prongs or pin-like curved hooks to enter the cuff material in such manner as to secure the unit thereto, the lever in turn being engageable with a part of the unit frame to lock it in place, the several parts of the unit presenting an ornate appearance, not out of harmony with the dictates of fashion. 65

Referring now in detail to that embodiment of the invention illustrated in the accompanying drawings, each unit comprises an open frame 1 preferably made of spring wire treated to simulate one of precious metal. Each unit frame as best shown in Fig. 3 consists of a pair of laterally spaced U-shaped frame members each including parallel top and bottom parts or legs 2 and 3 respectively connected together at one end by an integral right angle part 4. Said part 4 determines the relative spacing between the top and bottom legs 2 and 3, and this spacing is sufficient to receive the double thickness of cuff material found in a shirt cuff 5. In one unit the legs 3—3 are connected together by a cross bar 6 while in the other unit said legs are formed to provide a hook 7 to be engaged with the cross bar 6 to detachably connect both units together to hold the cuff in proper position upon the wrist. The free end of each part or leg 2 is formed to provide a loop or convolution 8 that terminates in a curved extension 9. In the loops 8—8 of each frame is mounted a pintle 10.

of the lever member so that said member is capable of a pivotal movement on said pintle.

16 indicates as a whole an operating and locking member for said pronged lever member best shown in Fig. 5. Said locking member which is also made of wire is in the form of a substantially rectangular open frame having side arms 17 and end members 18 and 19 respectively, the end member 18 connecting the outer ends of said arms 17 and including an operating loop 20 therein and the end members 19 each have a loop 21 arranged at a right angle thereto and engaging the ends of a pintle 22 which passes through the double loop of the arm 14.

The cuff fasteners comprising the units above described are primarily intended for use in connection with the double or turned over soft cuff 5 of a shirt sleeve, which type of cuff is at the present time the vogue. Such a cuff is generally of a length twice the ordinary cuff length and has a pair of button holes in each margin spaced inwardly from each edge thereof, the button holes of each pair being intended to register when the end portion of the cuff is folded over and back toward the sleeve proper. With a cuff of this kind, the fold not only becomes quickly soiled but rapidly wears out and in many instances causes the shirt to be discarded before its time.

I have shown such a folded cuff in Fig. 1 and with my improved fastener in place thereon, with one unit on one margin and the other unit on the other margin. Each cuff margin is inserted into the space between the arms 2 and 3 of an associated unit as far as it will go until the connecting member 4 engages the edges of said margins, the parts 2-2 being on the outer side of the cuff and the parts 3-3 being on the inner side thereof. With the bell crank lever member 11 and locking member 16 in position, as shown in Figs. 6 and 7, pressure is imposed upon the double loop arm 14 forcing the prongs 15 into the cuff material, the prongs facing toward the edge of said margin and extending almost parallel with and in the plane of the frame members 2-2 but not being exposed upon the inner side of said margins.

The pins or prongs 15 being curved and being pivoted close to the cuff, swing in an arc about the pintle 10 and the points of the prongs enter the cuff material slightly in advance of the pintle 10 and then swing between the side portions of the frame member. This brings the points around the pintle 10 and holds the cuff material snugly up against the frame and base portions of the hooks thus relieving the points thereof from such a pulling action as tends to spread the frame and prongs apart. In this movement of the prongs, the cuff material be-

tween said prongs is pulled into the space between the side members of the frame to provide a good tight grip thereon.

The pressure upon the double loop arm of the prong member may be easily imposed by grasping the member 16 and positioning it at about a right angle to said lever arm as shown in Fig. 6 and then pressing downwardly upon the same. When the lever member is in this position the member 16 is swung back toward the members 2-2 of the frame when the side arms 17-17 thereof will pass the convolutions 8-8 of said members 2 and the arms 19-19 will be brought under the curved extensions 9 of said convolutions and thus lock the operating member in place which in turn will hold the double looped arm 14 in position with the prongs embedded in but concealed by the cuff material as best shown in Figs. 1 and 2. The two cuff margins each with a unit in place thereon are brought together and the end 7 of one unit is then hooked into engagement with the cross bar 6 of the other unit and the cuff as a whole is thus fastened together thereby. It is to be noted that the hook part 7 does not point toward the edges of the cuff margins but points substantially in the same general direction as the connecting portions 4.

With such an arrangement, it is apparent that button holes are unnecessary in a cuff, which may be readily folded along that line giving the desired length of cuff or sleeve. Should the cuff become soiled or worn along said line, the units are removed and the cuff folded about other and different lines which will conceal the soiled or worn edge. Thus neatness of personal appearance may be retained by folding the cuff along new lines as may be necessary. Again more wrist room is available in cuffs without increasing the width thereof or quantity of material going into the same. The parts of the units exposed upon the cuff when in use prevents the appearance of a woven "rosette" and gives an ornate appearance thereto. It is simple in construction, may be made and sold at a low cost and gives additional wear to the cuff upon which it is employed. Again the units may be readily disconnected or separated when it is desired to "roll" the cuff upon the forearm and neither unit can accidentally become displaced from the cuff.

Another advantage gained in the use of my improved cuff fastener, is that the lateral margins of the cuff are held neatly together so that these margins do not gap or separate as when the usual links and cuff buttons are employed in their stead.

While in describing my invention I have referred in detail to the form, arrangement and construction of the various parts thereof, the same is to be considered as by way

of illustration only and not by way of limitation except as may be pointed out in the appended claims.

I claim as my invention:

5. 1. A cuff fastener comprising a pair of coacting units each embodying therein a member to embrace an edge portion of the cuff and means included in each unit and disposed on the outer surface of the cuff for securing each unit thereto, said units having parts arranged upon the inner surface of the cuff, adapted to detachably connect said units together.
10. 2. A cuff fastener comprising a pair of coacting units each embodying therein a member to embrace an edge portion of the cuff, and means included in each unit and operable to hook into the cuff from the outer surface thereof, said units having parts arranged upon the inner surface of the cuff adapted to detachably connect them together.
15. 3. A cuff fastener unit comprising a member adapted to embrace a marginal part of a cuff, means associated with said member and adapted to be detachably connected to said cuff by hooking into the same and a device engaging said hooking means and member respectively for releasably securing said means in its hooked position with respect to the cuff.
20. 4. A cuff fastener unit comprising a member adapted to embrace opposite sides of a marginal part of a cuff, a pointed hook pivoted with respect to said member and adapted when in one position to have a hooked engagement with a part of the cuff and means pivotally connected to the hook and adapted to be engaged with a part of the cuff embracing member for releasably securing the hook in hooked engagement with the cuff.
25. 5. A cuff fastener unit comprising a sub-

stantially U-shaped member adapted to embrace opposite sides of a marginal part of a cuff, a lever including a cuff engaging hook and an arm pivoted to said U-shaped member and means associated with said arm and adapted to engage with parts of said U-shaped member for releasably securing said lever when its hook is engaged in said cuff.

45. 6. A cuff fastener unit comprising a substantially U-shaped member adapted to embrace a marginal part of a cuff and having extensions on that end spaced from the edge of the cuff margin, a lever including cuff engaging hooks and an arm pivoted to said U-shaped member and an actuating member pivoted to said arm of said lever and adapted to engage under said extensions for releasably securing said lever when said hooks are engaged in said cuff.

50. 7. A cuff fastener unit comprising a double U-shaped wire frame including pairs of spaced arms adapted to engage opposite sides of the marginal portion of a cuff, one of said pairs of arms having loops at their free ends and extensions beyond said loops, a lever formed of wire and including cuff engaging hooks and an arm, means pivotally connecting said lever and loops, and a loop like operating member also made of wire pivotally connected to said arm and adapted when in one position to engage under said extensions to releasably secure said lever when said hooks are engaged in the cuff.

55. 8. A frame for a cuff fastener unit made of wire comprising two lateral spaced U-shaped parts each including top and bottom arms, with one end of both bottom arms connected together and with the free ends of both top arms formed to provide convolutions each terminating in an extension.

In testimony whereof, I have hereunto set my hand, this 1st day of November, 1927.

PETER L. MARKEY.
